TOY SANTA CLAUS BOOT WITH SPRING-UP HEAD

Perry Feuer, Roslyn, N.Y., assignor to Creative Creations Inc., New York, N.Y.

Filed Nov. 25, 1970, Ser. No. 26,165

Term of patent 14 years

Int. Cl. D21—01

U.S. Cl. D34—4

FIG. 1 is a right side perspective view of the design with the lid of the boot in closed position;

FIG. 2 is a left side perspective view of the boot with the lid and the Santa Claus head in the raised position;

FIG. 3 is a right rear perspective view of the design shown in FIG. 2.

I claim:

The ornamental design for a toy Santa Claus boot with spring-up head, as shown.
